(74) *Attorney, Agent, or Firm* — Daniel M. Cohn

(57) **CLAIM**

The ornamental design for a portable fan as shown and described.

DESCRIPTION

FIG. 1 is a perspective view of a portable fan showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an exploded perspective view of the portable fan;

FIG. 11 is another exploded perspective view of the portable fan; and,

FIG. 12 is another exploded perspective view of the portable fan.

The broken lines in the drawings depict portions of the portable fan that form no part of the claimed design.

1 Claim, 12 Drawing Sheets
